Specification for Design.

Patented Mar. 2, 1920.

Application filed October 6, 1919. Serial No. 328,920. Term of patent 14 years.

To all whom it may concern:

Be it known that I, JOHN W. DENMEAD, a citizen of the United States, residing at Akron, in the county of Summit and State of Ohio, have invented a new, original, and ornamental Design for Elastic Vehicle-Tires, of which the following is a specification, reference being had to the accompanying drawings, forming a part hereof.

The Figure 1 is a plan view of a portion of an elastic vehicle tire showing my new design, and

The Fig. 2 is a cross sectional view of same taken approximately on line 2, Fig. 1.

I claim:

The ornamental design for an elastic vehicle tire as shown.

JOHN W. DENMEAD.
